(57) **CLAIM**

The ornamental design for a combination key ring and fragrance dispenser, as shown and described.

DESCRIPTION

FIG. 1 is a front, left perspective view of the combination key ring and fragrance dispenser showing my new design;

FIG. 2 is a front elevational view thereof;

FIG. 3 is a left side elevational view thereof, the right side being a mirror image thereof;

FIG. 4 is a top view thereof;

FIG. 5 is a bottom view thereof; and,

FIG. 6 is a front view of the combination key ring and fragrance dispenser in an open configuration with the cap removed.

The thin solid lines in the views have been provided for the purpose of illustrating the uniformity of the planar surfaces and the contour of the curved surfaces and are not a claimed surface pattern.
